MULTICOLOR PRINTING PRESS

Joseph F. Loughery, Philadelphia, Pa., assignor
to The Duo Color Printing Press Company,
a partnership consisting of Joseph F. Loughery,
Max Gettes, and A. K. Brown

Application February 15, 1938, Serial No. 190,662

9 Claims. (Cl. 101—193)

My invention relates to printing machines and particularly relates to a machine for printing two colors in one operation on cards, cardboard, or paper of cut sizes.

Printing machines have been made to print two or more colors on paper, but such printing machines have generally been complicated and comparatively slow in operation.

Heretofore, two-color printed cards have been made, but such cards have been fed by hand, and such cards had to be fed through the press twice thus duplicating the same operation.

It is an object of my invention to provide a continuous flat plate printing press having set-up type or electrotype for printing two or more colors.

Another object of my invention is to provide a printing machine which is simple in construction and which will rapidly and accurately print cards or paper of any size in multicolors.

Another object of my invention is to provide a printing press wherein the printing head or ram moves in a vertical direction and also moves in a horizontal direction.

It is another object of my invention to move cards, upon which there is to be printing, in a horizontal direction in unison with the movement of the printing head whereby the time for the relative movement of the bed and the printing head is reduced to a minimum.

Another object of my invention is to convey a plurality of cards in a single definite direction but wherein the conveyor reciprocates in a rectilinear direction.

Another object of my invention is to have a reciprocating bed which will move the cards or cut paper forward in one direction but which will not move the cards or paper when the bed moves in the opposite direction.

A still further object of my invention is to arrange the elements on the bed so that but one card or paper is moved from a stack of cards or papers.

A further object of my invention is to construct a printing press wherein gears are eliminated.

A still further object of my invention is to provide a rotatable driving member for a two-color printing press wherein there is no dead center for the driving member.

Other objects of my invention are to provide an improved device of the character described, that is easily and economically produced, which is sturdy in construction and which is highly efficient in operation.

With the above and related objects in view, my invention consists in the following details of construction and combination of parts, as will be more fully understood from the following description, when read in conjunction with the accompanying drawings, in which:

Fig. 1 is a front elevational view of the printing press embodying my invention.

Fig. 2 is a fragmentary sectional view taken on the line 2—2 of Fig. 1.

Fig. 3 is a schematic view of my invention as the printing head is moving from left to right as Fig. 3 is viewed, and which will be designated as the 0° or 360° position of the printing press wherein a printing impression is being made.

Fig. 4 is a view similar to Fig. 3 except that the ram or printing carrier is being moved upwardly and the printing carrier is in its extreme right position as Fig. 4 is viewed and wherein the driving wheel has rotated counterclockwise 90°.

Fig. 5 is a front elevational view similar to Figs. 3 and 4 but wherein the driving wheel has rotated the printing ram to its forward position and wherein the entire printing head is in a vertically raised position—the driving wheel has rotated counterclockwise through 180°.

Fig. 6 shows a view similar to the views illustrated in Figs. 3, 4, and 5, but wherein the turning wheel has moved 270° and wherein the ram is about to descend for the printing operation.

Fig. 7 is a fragmentary perspective view of the platen bed or conveyor showing the rectilinear reciprocating central and fixed side members.

Fig. 8 is a fragmentary view of the end of the bed and a receiving tray which is inclined to rapidly receive the printed cards or paper. The mechanism whereby the receiving tray is automatically lowered is not illustrated.

It is to be noted that similar reference designations refer to similar parts through the description.

Referring now in greater detail to Figs. 1 and 2, I show a printing press comprising a base, generally designated as A, a printing chase carrier, generally designated as B, a pair of vertically positioned guide members, generally designated as C and C¹, mounted upon a guide member connecting plate, generally designated as C², and a bed or platen, generally designated as D. The printing carrier B is adapted to reciprocate in a vertical direction between the bearing guides C and C¹. The printing carrier or ram B has suitable rails, Fig. 2, in the lower part thereof for retaining a printing chase or type, which

chase faces in a downwardly direction. The chase has two type beds 8, 9, whereby one type bed 8 contains letters that are adapted to be inked with one color type of ink, e. g. as black ink, and the second bed 9 is adapted to print alongside of the first printing bed but is adapted to be inked with a red or second color type of ink. The inking is done by split inking rollers (not shown) which are suitably synchronized with the movement of the printing carrier whereby the type is inked when the carrier is off the bed D.

The ink plate and the ink foundation or inking rollers are not shown because ink tables and inking rollers as used on the standard printing presses may be used together with my invention. The inking rollers usually ink the type when the printing carrier B is at its highest position, and the inking rollers run over the ink table (not shown) while the type is in printing contact. Suitable means for this operation are well known to those skilled in the art.

The printing carrier B and the bearing guides C and C1 reciprocate laterally together, but the printing carrier B itself reciprocates vertically with respect to the laterally movable bearing guides, see Figs. 3, 4, 5 and 6. Hence, the bearing guides, the bearing guides connecting member C2, and printing carrier move horizontally together, but the printing carrier slides vertically upon the bearing guides.

A vertically positioned standard, generally designated as E, is suitably attached to the upper portion of the base A. The standard E serves to retain the printing carrier B in its vertical position and also serves to guide the printing carrier in its horizontal reciprocating movement by virtue of the connecting member C2.

A printing press driving wheel, generally designated as F, is suitably journaled on the rear of the standard E, and the wheel is rotated by a belt 10 (Fig. 2) which is suitably rotated by an electric motor (not shown).

The printing press driving wheel F is rigidly attached to a shaft 12 which is journaled in a bearing 14 on the standard E, and the outer end of the shaft has an offset crank arm 16 which fits into a bearing 18 in the printing carrier B; hence, the shaft 12 and the crank arm 16 rotates in unison with the rotation of the driving wheel F. It will be apparent from an inspection of Figs. 3 to 6, inclusive, that the crank arm 16 moves the printing carrier B up and down and from one side to the other side as the crank arm 16 moves about a circle, the radius of the circle being the distance the center of the crank arm is from the center of the shaft 12.

The motion of the carrier B will be a harmonic motion, and the carrier B will move the bearing guides C, C1 from side to side since the bearing guides are connected together by member C2. The vertically extending standard E has aligned plates 20, 22 in which there are horizontally located elongated slots 24, 26, respectively, into which slots each of the guide plates C and C1 have a journal or stud 28 interfit. The portion of the standard E defining each of the slots 24, 26 form guide bearings for the interfitting journals 28, thereby limiting the movement of the plates C and C1 only in a reciprocatory horizontal direction.

The platen or bed

The platen or bed D, which is that part of the printing press on which the cards G1, G2, G3, G4,

G5, G6 and G7 are supported, moves horizontally in perfect unison with the lateral movement of the printing carrier B because the platen D is rigidly tied to the horizontally movable standard E by means of the supporting arms 30 and 32 5 (Figs. 1 to 7).

The bed D, Fig. 7, reciprocates between two stationary angle-irons 34, 36 which serve to hold the blank cards upon which printing is to be impressed in a definitely aligned position. The platen D is an elongated flat metal member having along each of its vertically extending side edges a plurality of pivotal pusher arms or fingers, each of which will be generally designated as H. The pusher finger is pivoted at 38 and has 15 an angularly extending upper edge 40 which widens as the free end of the arm is approached. The forward lower end extension 42 of the pusher arm H is bent at an angle of substantially 90° so that it engages a portion of the lower surface 20 of the platen D. A spring 46 engages the extension 42 and tends to press the extension upwardly. The pusher fingers are arranged in pairs so they push a card forward, and on the backward stroke of the pushers, they are depressed or slide 23 under the card. A plurality of holding arms H1 are constructed similarly to the pusher arms H, but the holding arms are located upon the inner vertical sides of the angle irons 34 and 36 (Fig. 7).

A flat bar 47 overlaps the top of the angle-iron 34, the pusher fingers H and holding fingers H1 on one side of the bed, and a flat bar 49 is similarly arranged over the angle-iron 36 and the other side of the bed. Each of the bars 47, 49 are adapted to hold the side edges of the cards upon the platen D.

Each holding arm or finger H1 is pivoted as at 48 (Fig. 7) to the vertical edge of the flange 50 of the rail or angle-iron. The upper edge of 40 the holding finger 52 is inclined so that the arm widens in the direction of the unsupported end. A short side extension 54 projecting at an angle of approximately 90° to the main body portion of the arm is adapted to abut a portion of the underside of the horizontally extending flange. A spring 56 tends to press against the extension so that the free end of the holding arm is pressed upwardly. The holding arms H1 and the pushing arms H cooperate to move the cards along 50 in the following manner: The blank card is pushed along by the pushers H at a distance equal to that between the centers of each different chase. After the card has been moved along, the pushers move backwardly and ride under the card; however, to prevent the card from moving backwardly, it engages the holding arms until the next set of pushers move the card forward another unit distance. The card thus travels in a series of steps from the front stack 55 to the end of the bed or platen. In other words, the fingers on the bed must push each card beyond fingers on the rails.

The card stack holder

Since it is desirable to automatically feed the blank cards or papers under the printing ram, the cards are placed within suitable holding vertically extending uprights 60, 61, which are suitably spaced so the cards or paper are definitely aligned to land upon the bed or platen. The cards being located above the platen are gravity fed, and a small adjustable card gage 62 positioned directly above the platen permits but one card to be pushed along the platen. If the thickness of the 75

cards in one stack is different from the thickness of the cards in another stack, then the card gage may be adjusted by a screw 63 to accommodate the thickness of the card.

- 5 In operation the bottommost card, for example card G1, falls upon the platen D. The card G1 is pushed forward by the pusher arms H, but one card is pushed forward, however, because of the card gage 62. As the bottommost blank card G1 10 starts on its journey, it is pushed to the right by the pusher arms H. The next card G2 at once takes the place previously occupied by that card pushed out. This operation is repeated until the first card G1 is in the proper position to receive 15 the desired first colored impression from the type 8, and the card G1 is moved forward until it is in position on the conveyor system whereby the card receives its second colored impression from type 9 after which it is continually moved onward in 20 steps until it is dropped off the conveyor into an angularly inclined retainer, generally designated as H. A continual succession of blank cards are conveyed along the platen D and printed in two colors. It should be particularly noted that two 25 colors are simultaneously impressed on two cards at one impression, and at each impression, one card succeeds to the position previously held by the other card. Hence, two cards are automatically printed in two colors in two cycles of the 30 printing head.

It is essential to have the receiver H of the printed cards disposed at the angle at which the printed cards fall from the bed D because of the great rapidity with which cards are printed. The 35 receiver H is also automatically lowered by suitable mechanism as each card falls into it.

Miscellaneous

A "trip" or adjustable means to keep the printing chase from making any impression upon the cards or platen are provided but are not shown in the drawings as such means are commonly used on printing presses.

The container for catching the printed cards or paper may be fitted with mechanisms to lower the container as the printed cards or paper drop therein. Such mechanism also is not shown in the present drawings as it would tend to obscure the more important part of invention herein- 50 before disclosed.

A recapitulation of my invention is as follows:

The impressions to be made are set up so that the impression of one color is set in a printing 55 form and the impression of the second color is set in a second printing form so that the multi-color printing will register. Thus, two separate and distinct sets of printing forms 8, 9, are placed in the bottom of the printing carrier B.

60 The inking plates are properly inked with their respective suitably colored ink. A stack of blank cards or stock are placed in the feeder, and the card gage 62 is set for the individual thickness of the stock, and the driving wheel is rotated. As 65 the wheel F rotates it moves the printing carrier vertically up and down, by virtue of the crank-arm 16, to make the printed impressions, and the crank-arm 16 moves the guides C, C1 and their connecting plate C2 as well as the carrier in a 70 transverse direction. This transverse reciprocatory movement of the guides also carries the bed D, and because of the series of pusher fingers H on the bed as well as the holder fingers H1 on the stationary side members or rails, the cards are 75 moved along the platen in a series of steps. It is

to be remembered that the fingers H on the bed push the cards beyond the front of the fingers H1 on the rails in order to prevent the card from going back with the reverse stroke of the bed.

As the first card G1 comes under the first set of 5 type 8, it has an impression made thereon in the next cycle of the driving wheel. The card G1 is moved to a position on the platen where it receives the second type impression 9, while the second card G2 simultaneously receives the first 10 type impression 8. The first card G1 is moved along in the next cycle of the driving wheel, and the second card G2 takes the place of the first card, while a third card G3 succeeds to the position of the second card G2, and this cycle of 15 events is repeated to print a two-color card.

Of course, if more than two colors are desired to be impressed, then the printing carrier must have a printing form for each color. As an example, if a three-color card is to be printed then 20 the chase must have three sets of type arranged to complementary register upon the stock.

Although my invention has been described in considerable detail, such description is intended as illustrative rather than limiting, since the invention may be variously embodied, and the scope 25 of the invention is to be determined as claimed.

I claim as my invention:

1. In a printing press a printing head, means to move said printing head vertically and horizontally, a bed for holding a plurality of cards to be printed, and means for moving said cards in a rectilinear direction, a horizontally movable member upon which said printing head vertically moves, said bed rigidly attached to said horizontally movable member. 35

2. In a two-color printing press a vertically movable printing carrier, a plurality of sets of type in the lower portion of said printing carrier, a guide bearing for said printing carrier, a platen rigidly attached to said guide bearing whereby the platen will move in a rectilinear direction, means movable with said platen to move cards-to-be-printed in only one direction, and means whereby said guide bearing and said 40 printing carrier may transversely reciprocate in unison. 45

3. In combination with a printing press a printing head, means to oscillate said printing head in a vertical as well as a horizontal direction, a translatory reciprocable bed, a plurality of spring pressed pivoted fingers mounted upon 50 said bed, said fingers adapted to push a card in one direction and to pass under said card when it moves in the opposite direction, and means 55 to prevent cards from moving in one direction.

4. In a two-color printing press a driving wheel having a crank arm, a freely movable printing carrier, a complementary bearing to receive said carrier, a guide for said printing carrier, said 60 guide having a pair of studs thereon, a fixed standard having a pair of horizontally positioned slots adapted to complementarily receive said pair of studs whereby the guide may reciprocate in a rectilinear direction, a plurality of sets of 65 printing type on said printing carrier, and a translatory reciprocal printing bed rigidly connected to said studs adapted to carry cards in but one direction and synchronized in movement with said printing carrier. 70

5. In a two-color printing press a driving wheel having a crank arm, a freely movable printing carrier adapted to move vertically and horizontally, a complementary bearing to receive said carrier, a guide for said printing carrier, said 75

guide having a pair of studs thereon, a fixed standard having a pair of horizontally positioned slots adapted to complementarily receive said pair of studs whereby the guide may reciprocate 5 in a rectilinear direction, a plurality of sets of printing type on said printing carrier, and means for carrying cards adapted to oscillate from under one set of printing type to the other set of printing type, said means including a platen 10 rigidly connected to said guide.

6. A multicolor card printing press comprising a vertically movable printing head, a horizontally movable guide for said printing head, a platen rigidly connected to said guide, said platen 15 having a spring pressed finger adapted to push cards comprising a thin flat member, said flat member pivotally mounted, an inclined upper edge on the thin portion of said flat member, a substantially vertical edge joining said inclined 20 edge whereby said edge forms an acute angle, a lateral extension on said finger, and a spring adapted to engage said extension to press said member in one direction about the pivot point.

7. A printing press comprising a vertically movable printing head, a horizontally movable guide for said printing head, a reciprocable center platen, said platen being rigidly connected to said 25 guide member, a plurality of fixed rails, one rail adjacent each side edge of said center member, a plurality of aligned pairs of spring-pressed fingers on said center member, and a plurality of spring-pressed fingers on each of said side members being aligned in pairs and being located so that the fingers on the bed push the 30 cards beyond the fingers on the rails.

8. In a two-color printing press a driving wheel having a crank arm, a freely movable printing carrier, a complementary bearing to receive said 35

carrier, a guide for said printing carrier, said guide having a pair of studs thereon, a fixed standard having a pair of horizontally positioned slots adapted to complementarily receive said pair of studs whereby the guide may reciprocate 5 in a rectilinear direction, a plurality of sets of printing type on said printing carrier, means for carrying cards adapted to oscillate from under one set of printing type to the other set of printing type, a bed comprising a reciprocable 10 elongated center member, a gravity feed box, an angularly disposed receiver for the matter printed, and means to automatically lower said receiver.

9. In a two-color printing press a driving wheel 15 having a crank arm, a freely movable printing carrier, a complementary bearing to receive said carrier, a guide for said printing carrier, said guide having a pair of journals thereon, a fixed standard having a pair of horizontally positioned 20 slots adapted to complementarily receive said pair of journals whereby the guide may reciprocate in a rectilinear direction, a plurality of sets of printing type on said printing carrier; means for carrying cards adapted to oscillate 25 from under one set of printing type to the other set of printing type, said means comprising a reciprocable elongated center bed member, a plurality of fixed rails, one rail adjacent each side edge of said center member, a plurality of aligned 30 pairs of spring-pressed fingers on said center member, and a plurality of spring-pressed fingers on each of said rail members, said fingers on the rail members being aligned in pairs and being located so that the fingers on the bed are 35 adapted to push the cards beyond the fingers on the rails.

JOSEPH F. LOUGHERY.
